UNITED STATES PATENT OFFICE

165,790

VEHICLE TRIM LOUVER OR SIMILAR ARTICLE

William E. Robinson, Detroit, Mich., assignor to
Packard Motor Car Company, Detroit, Mich.,
a corporation of Michigan

Application March 26, 1951, Serial No. 14,616

Term of patent 7 years

(Cl. D14—6)

To all whom it may concern:

Be it known that I, William E. Robinson, a citizen of the United States, residing at Detroit, county of Wayne, State of Michigan, have invented a new, original, and ornamental Design for a Vehicle Trim Louver or Similar Article, of which the following is a specification, reference being had to the accompanying drawing, forming a part thereof.

Figure 1 is a side view of a vehicle trim louver, showing my new design.

Figure 2 is an end elevation thereof;

Figure 3 is a bottom view of the louver shown in Figure 1;

Figure 4 is a side elevational view thereof wherein the broken lines indicating an automobile are for illustrative purposes only.

Those portions shown in the drawing by means of dotted lines are for illustrative purposes only.

I claim:

The ornamental design for a vehicle trim louver or similar article, substantially as shown and described.

WILLIAM E. ROBINSON.
